[57] CLAIM

The ornamental design for a “gun sight,” as shown and described.

DESCRIPTION

FIG. 1 is a perspective view of gun sight showing our new design;

FIG. 2 is a right side elevational view of the gun sight shown in FIG. 1, the left side elevational view being a mirror image thereof;

FIG. 3 is a top plan view of the gun sight shown in FIG. 1; FIG. 4 is a bottom plan view of the gun sight shown in FIG. 1; and,

FIG. 5 is a front elevational view of the gun sight shown in FIG. 1, the rear end elevational view being a mirror image thereof.
